UNITED STATES PATENT OFFICE.

JOHN A. ORMAN, OF ASHLAND, MONTANA.

BROOM-HANGER.

1,305,486.

Specification of Letters Patent. Patented June 3, 1919.

Application filed November 16, 1918. Serial No. 262,821.

To all whom it may concern:

Be it known that I, JOHN A. ORMAN, a citizen of the United States, residing at Ashland, Mont Rosebud county, and State 5 of Montana, have invented and discovered certain new and useful Improvements in Broom-Hangers, of which the following is a specification.

My said invention relates to broom hang- 10 ers or racks and has for its object to provide a convenient means for supporting a broom when not in use. The device is of the type constructed of a single piece of wire bent in the proper form, and consists in certain im- 15 provements in the details of form and ar- rangement, whereby such a device is adapt- ed for convenient and easy reception and removal of the broom, and provided with appropriate eyes for the reception of means 20 for securing the device to the support, all as will be hereinafter fully described and illustrated in the accompanying drawing, in which is shown a single figure represent- ing:

25 A perspective view of a broom hanger, secured to a wall, with the broom indicated therein by dash lines.

The device is composed of a single piece of wire formed with an eye 5 from which 30 horizontal portions 6 and 7 extend each way for a distance and are then bent downward and inward toward each other until they nearly meet, thereby forming a pair of 35 looped wings 8 and 9 which form a base and support the device firmly against the wall or other part to which it may be attached. The branches of the wire are then 40 bent at right angles so as to extend straight down forming parallel portions 10 and 11 for an appropriate distance, each being then 45 bent upward to form a hook-shaped part and doubled over at points 16 and 17 forming a pair of horizontally disposed semi-circular members 12 and 13 at their lower 50 ends, twisted together and terminating in a pair of upstanding diverging prongs 14 and 15. The single ends extend upward in close relation and are each formed with a loop, 18 and 19 respectively, which, like the eye 5, are designed to receive a screw for se-

curing the holder to a wall or other suitable support.

By means of this construction it is not necessary to insert the end of the broom handle in the circular portion formed by 55 the members 12 and 13 because the prongs 14 and 15 are so flexible that they may be sprung apart for the ready insertion of the base or head of the broom or the end of the handle to which the broom head is at- 60 tached.

It will be understood, of course, that any type of broom or like implement may be 65 cared for by this device, and supported in a manner to protect the implement as well as to serve the convenience of the user.

Having thus fully described my said in- 70 vention, what I claim as new and desire to 75 secure by Letters Patent is:

1. A broom hanger composed of a single 70 piece of wire having a centrally formed eye to receive an attaching device and bent to form laterally projecting wall engaging wings, the ends of the wire being bent out- 75 wardly to form a loop adapted to receive the shoulder of the broom, upwardly to form divergent prongs to engage the face of the broom head, then back upon itself through said prong and loop forming portion, the extreme ends of the wire being brought to- 80 gether and formed with eyes adapted to re- 85 ceive a further attaching member.

2. A broom hanger composed of a single 85 piece of wire formed with an eye to receive an attaching device and bent to form later- 90 ally projecting wall engaging wings and vertical substantially parallel hook-shaped members with diverging prongs, the ex- 95 treme ends of the wires being brought to- gether in a central position and formed with eyes adapted to receive another attach- ing member, substantially as set forth.

In witness whereof, I have hereunto set my hand and seal at Baltimore, Md., this 2nd day of November, A. D., nineteen hun- 95 dred and eighteen.

JOHN A. ORMAN. [L. S.]

Witnesses:

FRANK J. SCHUSTER,
FRANK J. CORRIGAN.
